UNITED STATES PATENT OFFICE.

HENRY E. BANDLOW, OF CHICAGO, ILLINOIS.

DESIGN FOR A LAMP.

42,078.

Specification for Design.

Patented Jan. 9, 1912.

Application filed September 28, 1910. Serial No. 584,382. Term of patent 7 years.

To all whom it may concern:

Be it known that I, HENRY E. BANDLOW, a citizen of the United States, residing at Chicago, in the county of Cook and State of Illinois, have invented a new, original, and ornamental Design for Lamps, of which the following is a specification, reference being had to the accompanying drawing, forming part thereof.

Figure 1 is a side elevation of a lamp showing my design. Fig. 2 is a plan view thereof.

I claim:

The ornamental design for a lamp, as shown.

HENRY E. BANDLOW.

Witnesses:

W. L. HALL,
WILLIAM GOLDBERGER.
